ADJUSTABLE CLOTHING DISPLAY RACK

Daniel E. Gelles, 1140 Broadway,
Kerhonkson, N.Y. 10001

Filed June 18, 1971, Ser. No. 154,709

Term of patent 14 years

Int. Cl. D6—06

U.S. Cl. D6—85

FIG. 1

FIG. 2

FIG. 3

FIG. 4

FIG. 5

FIG. 6

FIG. 7

FIG. 1 is a perspective view of an adjustable clothing display rack showing my new design,

FIG. 2 is a fragmentary enlarged view taken on line 2—2 of FIG. 1,

FIG. 3 is a top plan view thereof,

FIG. 4 is a bottom plan view thereof,

FIG. 5 is a left side elevational view thereof,

FIG. 6 is a right side elevational view thereof; and

FIG. 7 is a top plan view thereof, showing the clothing supports in an adjusted position.

I claim:

The ornamental design for an adjustable clothing display rack, substantially as shown and described.
